PROPELLER TYPE FAN CONSTRUCTION

Theodor H. Troller, Akron, Ohio, assignor to
 La-Del Conveyor & Manufacturing Co., New
 Philadelphia, Ohio, a corporation of Ohio

Application June 15, 1938, Serial No. 213,775

1 Claim. (Cl. 230—120)

The invention relates generally to apparatus for moving fluids, and more particularly to rotary fan construction adapted to produce exceptionally high efficiencies.

5 In my prior Patent No. 2,040,452, issued May 12, 1936, and entitled Fan construction, the reduction in efficiency of rotary fans due to the component of movement of the fluid transverse of its delivery direction is fully discussed, and 10 the patent teaches how to counteract said component by the use of straightener vanes and thereby increase efficiency of the fan.

Said patent also mentions the tendency of a 15 propeller fan to produce a condition at the center of the air stream behind the propeller, where the air is substantially stationary and substantially no pressure is being built up. It is well known that this condition can be largely overcome by providing a cylindrical inner casing or 20 fairing coaxial with the outer fairing or delivery duct, which inner casing occupies the space behind the propeller where pressure would not be properly built up by the propeller.

The present invention provides for utilizing 25 straightener vanes of novel construction and arrangement for attaining higher efficiencies, which vanes are adapted to be combined with certain improved conduit constructions to produce novel and useful results.

30 Straightener vanes should eliminate as far as possible the tangential component of fluid flow transverse to the delivery direction, and in eliminating this component static pressure should be built up in the air stream equal to the energy 35 of the tangential component of the velocity. In such conversions of velocity into static pressure, there is a tendency toward building up layers of fluid with slowed down velocity near the walls or all surfaces past which the fluid flows, and 40 this condition may cause losses in energy to the extent of completely breaking down the flow pattern. Such losses may be particularly pronounced in fans of relatively small diameter because the smaller the diameter the greater is 45 the amount of surface past which the fluid flows, in proportion to the volume of the air stream.

It is therefore an important object of the present invention to provide a propeller type fan construction which substantially avoids losses 50 in energy of the air stream connected with its reduction in velocity while passing through straightener vanes.

A further object is to avoid such losses by correlating the design of the straightener vanes 55 and their action on the air stream so as to prop-

erly regulate the slowing down of the fluid in passing through the vanes.

Another object is to provide a propeller type fan construction having an outer conduit which varies in cross-sectional area according to the 5 divergence of the straightener vanes surrounded by said outer conduit.

These and other objects are accomplished by the combinations, arrangements, constructions, and relationships of the parts, elements and improvements comprising the present invention, which is disclosed and described herein, and defined in the appended claim.

In general terms the invention consists in constructing a propeller type fan having straightener vanes so constructed as to properly straighten the flow of fluid and at the same time diverging gradually and uniformly from each other, such vanes being adapted to be used with an outer duct converging in area over the straightener vanes.

In the drawings forming part hereof, I have shown a relatively small portable propeller type fan embodying the invention, but it will be understood that the invention may be applied to 25 various sizes of fans, as well as to stationary propeller type fans.

Figure 1 is a longitudinal view of the improved fan showing the outer fairing in cross section, the rotating propeller and inner fairing 30 in elevation, and the straightener vanes being shown in cross section at their respective junctions with the outer fairing;

Fig. 2 is an end view looking toward the entrance end of the fan;

Fig. 3 is a similar end view with the propeller blades being broken away to show the straightener vanes;

Fig. 4 is an enlarged diagrammatic developed view of two of the straightener vanes, the cross 40 sectional shapes thereof at the inner fairing being represented in a single plane; and

Fig. 5 is a diagrammatic view showing the rate of divergence between opposing surfaces of adjacent blades.

Similar numerals refer to similar parts throughout the several views of the drawings.

The portable propeller type fan which is shown in the drawings is adapted to various uses, and is particularly suitable for use in a mine 50 where it is desired to convey air from a main ventilated tunnel a considerable distance through a laterally extending entry leading from the tunnel to a room at the working face. In using the fan for this purpose it may be positioned in the 55

entry at its connection with the main tunnel, and by connecting a delivery duct or conduit to the discharge end of the fan, the air for ventilation may be delivered at the outer end of the room 5 where the material is being mined.

The improved fan may be mounted upon a suitable base consisting of skids or runners 6 extending longitudinally of the fan and connected to the outer conduit or fairing indicated generally at 7 by means of plates 8 in such a way that the runners 6 are preferably parallel with the longitudinal axis of the fan.

The hub 9 of the propeller preferably has at its entrance end a suitably rounded nose indicated at 10 and is preferably secured on a motor shaft 11 for being driven by a motor 12 which is mounted within the inner fairing 13. A plurality of radially extending propeller blades 14 are secured to or integral with the hub, four of 20 such blades being shown in the drawings. The blades 14 may be of substantially standard design, having a greater pitch at the hub than at their outer ends, and are designed to deliver air in the direction of the arrows in Fig. 1 when rotated counter-clockwise in the direction of the arrow in Fig. 2.

The inner fairing 13 is coaxial with the outer fairing 7 and is supported therein by a series of circumferentially arranged vanes 15 preferably located behind or downstream from the blades 14 and secured at their inner ends to the inner fairing 13 and at their outer ends to the outer fairing 7. Electric conductors for supplying current to the motor 12 may be passed through suitable 35 passages in one of the vanes 15, if desired.

The entrance or upstream end of the inner fairing 13 is preferably cylindrical and conforms in diameter to the hub 9, and the delivery end 16 may be tapered down to a point substantially 40 in accordance with the shape of a conventional airship hull, so as to present a minimum of resistance to the air flow.

The entrance end of the outer fairing is preferably outwardly flanged as shown at 18, in accordance with the usual practice, and that portion of the outer fairing which surrounds the propeller blades 14 is cylindrical as shown at 19 and of sufficient diameter to provide a slight clearance between its inner surface and the outer 50 ends of the blades 14.

The portion 20 of the outer fairing which surrounds the vanes 15 and to which the outer ends of the vanes are secured, may be and preferably is tapered or converged inwardly from the upstream ends to the downstream ends of the vanes to form a conical section extending throughout the lengths of the vanes, for a purpose to be described.

From the downstream end of portion 20 to 60 the delivery end of the outer fairing, the outer fairing may be and preferably is formed cylindrical as indicated at 21.

In designing the straightener vanes 15, their general shape and contour may be calculated according to engineering practice or from the formulae given in my prior Patent No. 2,040,452, but neither of these methods gives any definite data on the amount and rate of divergence between adjacent vanes as measured at intervals throughout the curvilinear lengths of opposing surfaces of the adjacent vanes from their entrance to their delivery ends.

I have found that by gradually and substantially uniformly increasing the distance between 75 the surfaces of adjacent vanes measured perpen-

dicular or normal to the direction of the air flow therebetween, the desired axial movement of the air stream at the delivery ends of the vanes is obtained with a minimum of energy losses connected with the reduction in velocity of the air stream in passing through the vanes.

Fig. 4 is substantially a development in a single plane of two adjacent vanes 15 and 15' taken at their radially inner ends where they connect with the cylindrical outer surface of the inner fairing 13. The corresponding surfaces of the vanes are indicated by the curved lines 23 and 23', and the curved lines 24 and 24', respectively, the opposing surfaces of the adjacent vanes being indicated at 24 and 23' respectively, and 15 forming an air channel therebetween.

The angle of the entrance ends of the vanes with the longitudinal axis of the propeller substantially coincides with the direction of movement of the air delivered by the propeller through 20 the vanes as indicated by the arrow 25 in Fig. 4, which direction of movement is the resultant of the axial and transverse components of movement produced by the propeller blades.

The cross sectional shape of the vanes at the 25 inner fairing as represented in Fig. 4 is necessarily such that the distance measured circumferentially between corresponding surfaces 23 and 23' and between corresponding surfaces 24 and 24' is equal throughout, as represented by 30 the distance y measured vertically in diagrammatic Fig. 4 between corresponding surfaces at points taken at random. At the same time the design of the vanes is such that the width of the air channel between opposing surfaces 24 and 23' 35 increases gradually and at a substantially uniform rate from the entrance end to the exit end of the channel between the vanes.

By way of example, the rate of divergence between the opposing surfaces of adjacent vanes 40 may be shown as indicated in Figs. 4 and 5. In Fig. 4 the median line $x-x$ representing the direction of fluid flow is laid out between surfaces 24 and 23' and a series of points A to I laid out at intervals thereon. At these points the distances a to i to the opposing surfaces 24 and 23' 45 is measured in directions perpendicular or normal to the tangents to line $x-x$ at those points.

Now if the line $x-x$ is laid out as a straight line as shown in Fig. 5 and the points A to I are 50 laid out at the same intervals thereon, the distances a to i measured in opposite directions from line $x-x$ and perpendicular thereto will determine points through which inclined straight lines 24 and 23' may be drawn corresponding to the 55 curved lines 24 and 23' in Fig. 4. The angles Q which the inclined straight lines 24 and 23' make with the straight median line $x-x$ should be approximately 11° , and may vary from 11° to say 13° , although I do not wish to be limited to these 60 exact figures. This divergence is equivalent to an increase in width of approximately one unit in five units of axial length.

Due to the difficulties in accurately designing the cross sectional shape of the vanes in order to 65 obtain the desired results, it may be that in the intervals from A to B and from B substantially to C, the distances from the median line $x-x$ to the surfaces 24 and 23' will be substantially constant, as represented in Figs. 4 and 5, but this has no 70 appreciable effect on the results obtained at the delivery end of the channel between two adjacent vanes. As shown in Figs. 4 and 5 from the point C to the point I at the delivery end of the vanes, the width of the channel measured perpendicu- 75

lar or normal to the direction of air flow increases at a uniform rate.

In the example given, if the velocity of the air entering the vanes in the direction of arrow 25 is approximately 15 feet per second, I have found that the velocity at the delivery end of the vanes in an axial direction will be approximately 12 feet per second, if the portion 20 of the outer fairing surrounding the vanes is cylindrical. By 10 designing the vanes in order to produce the gradual and uniform divergence therebetween, as previously described, this reduction in velocity of the air stream is properly regulated so as to substantially avoid losses in energy, with the result that 15 very high efficiencies are attained.

The efficiency of the straightener vanes in transforming the energy connected with the circumferential component of the air velocity behind the propeller into other useful energy can 20 often be further increased by converging the portion 20 of the outer conduit by an amount up to the amount of divergence between the vanes. This converging of the outer conduit 20 is useful not only when the higher energy contained in 25 the higher axial velocity is immediately useful, but I have found that often, even though this axial velocity energy must be transformed by a following diffusor into static energy, the overall efficiency of the total arrangement is better than 30 that of vanes with a cylindrical outer conduit 20.

I have found that in the example given, by varying the cross sectional area of the portion 20 of the outer fairing equivalent to reducing its diameter from the entrance end of the vanes to 35 the delivery end by one unit in a vane length measured axially of fifteen units, the axial velocity of the air stream at the delivery end of the vanes will be approximately equal to the velocity at the entrance end in the direction of arrow 25, or 15 feet per second.

In other words, the amount of convergence of the portion 20 of the outer fairing is calculated to produce an axial velocity at the delivery end of the vanes substantially equal to the velocity 45 of the air at the entrance end in the direction of its movement at that point. The convergence of

the portion 20 should not be too sharp because no material gain in reducing the straightening losses could be expected thereby, whereas the friction on the wall and vane surfaces would be increased due to the resulting high velocity so as 5 to give rise to new sources of losses in energy.

Thus by combining the gradual and uniform divergence of the straightener vanes with a corresponding convergence of the outer fairing around the vanes, the axial velocity of the air 10 flow after passing through the vanes is substantially equal to its velocity in the direction of flow entering the vanes, and the energy losses in passing through the vanes are substantially avoided 15 by the design and divergence of the vanes, thus providing a propeller type fan attaining extremely high efficiencies.

I claim:

Propeller fan construction including a longitudinally extending outer fairing, a streamlined 20 inner fairing coaxial with the outer fairing, a propeller mounted for rotation in said outer fairing axially thereof for delivering fluid through said fairing, a series of circumferentially arranged straightener vanes secured to said outer 25 and inner fairings axially adjacent to said propeller, the entrance ends of said vanes being disposed at an angle substantially equal to the angle 30 of fluid flow delivered by said propeller and said vanes being curved throughout their lengths to bring their delivery ends in axial alignment with said fairings, the distance between opposing surfaces of adjacent vanes measured in a direction 35 normal to the fluid flow between said vanes being gradually increased at a substantially uniform rate from the entrance ends to the delivery ends 40 of said vanes, and the portion of the outer fairing surrounding the vanes being converged from the entrance ends to the delivery end thereof by an amount so related to the divergence between 45 adjacent vanes as to produce an axial fluid velocity at the delivery ends of the vanes not greater than the total velocity of the fluid in the direction it enters the vanes from the propeller.

THEODOR H. TROLLER.
